MACHINE FOR INSERTING FASTENINGS.

1,258,392.

Specification of Letters Patent.

Patented Mar. 5, 1918.

Application filed June 21, 1915. Serial No. 35,337.

To all whom it may concern:

Be it known that I, THOMAS BRIGGS, a subject of the King of England, residing at Leicester, Leicestershire, England, have 5 invented certain Improvements in Machines for Inserting Fastenings, of which the following description, in connection with the accompanying drawings, is a specification, like reference characters on the drawings 10 indicating like parts in the several figures.

This invention relates to machines for inserting fastenings and the general object of the invention is to provide an improved machine of this class especially adapted for 15 use in the manufacture of boots and shoes.

The invention is herein shown as embodied in a machine of the type which inserts a plurality of previously formed fastenings successively in a shoe to form a row, a machine 20 of this type being commonly known as a "loose nailing machine" and comprising usually a nail driving mechanism, a raceway mechanism for conducting headed nails from a source of supply to a point adjacent to the driving mechanism, a separator for separating the endmost nail from the line of 25 nails in the raceway and delivering it to the driving mechanism, and an awl for forming successively nail receiving openings 30 in the shoe and having generally and preferably the further function of feeding the shoe between successive nail driving operations.

In the manufacture of boots and shoes, it 35 is frequently desired in attaching soles to shoes to drive a plurality of rows each comprising successively inserted previously formed headed nails, such nailing when two rows of nails are inserted, being commonly 40 termed "double row nailing." Fastening inserting machines have been designed for forming fastenings from a continuous strip of material and inserting a plurality of rows of those fastenings in a shoe. Also, heel 45 attaching machines have been designed for inserting a plurality of rows of nails in the heel of a boot or shoe. So far as I am aware, however, no machine has been proposed heretofore intended for or capable of handling in bulk and inserting simultaneously 50 in the heel of a boot or shoe a plurality of rows of previously formed fastenings, such, for example, as headed nails, to perform the before mentioned double row nailing oper-

ation upon a shoe. Consequently, before 55 the present invention it has always been necessary whenever it was desired to perform this operation first to insert one row of nails and subsequently to insert the second row of nails. 60

One of the objects of the present invention is to provide a fastening inserting machine capable of inserting simultaneously in a shoe a plurality of rows of previously formed fastenings when desired, thus avoiding the 65 expense and loss of time necessarily involved in double row nailing as heretofore practised.

In accordance with this object of the invention, in addition to mechanism for inserting a plurality of fastenings successively in a shoe to form a row, raceway mechanism for supplying previously formed fastenings to the inserting mechanism and separator mechanism for governing the supply of fastenings from the raceway mechanism to the 70 fastening inserting mechanism, the illustrated machine is provided with an auxiliary fastening inserting mechanism, whereby a plurality of rows each comprising successively inserted fastenings may be inserted in a shoe simultaneously. In the embodiment herein shown, the machine is provided with auxiliary awl mechanism and auxiliary separator mechanism, as well as 75 auxiliary driving mechanism, together with means for throwing the auxiliary awl and separator mechanisms into and out of operation 80 so that one or more rows of fastenings may be inserted at the will of the operator. 85 Preferably, and according to a feature of the invention, the construction and arrangement are such that the auxiliary awl and separator mechanisms may be thrown into and out of operation simultaneously. To 90 this end, as shown, the operation of the auxiliary separator mechanism is controlled by the auxiliary awl mechanism so that when the auxiliary awl mechanism is thrown into or out of operation, the operation of the 95 auxiliary separator mechanism is thereby initiated or suspended.

A further feature of the invention consists in automatic mechanism which insures that the auxiliary awl and separator mechanisms can only be thrown into or out of 100 operation at a proper point in the cycle of operations of the machine. In accord-

ance with this feature of the invention, provision is made for automatically locking the auxiliary awl and separator mechanisms against movement either into or out of operation while the shoe is being fed. For this purpose, the illustrated machine is provided with a controller governing the initiation and suspension of the auxiliary awl and separator mechanisms and a locking member 10 operated automatically upon shoe penetrating awl movement to lock the controller and hold it locked against further movement until the end of the shoe feeding movement, the controller being thereafter automatically unlocked.

Other objects and features of the invention will be apparent from the following detailed description read in connection with the drawings.

20 The invention will be described as applied to a loose nailing machine of the general type disclosed in United States Letters Patent No. 490,624, granted January 24, 1893, on an application of Louis Goddu, to which Letters Patent reference may be had for detailed description and explanation of various features of the illustrated machine not set forth fully herein. It is to be understood, however, that it is recognized that the invention as a whole or various features thereof may have other uses including use in loose nailing machines of other types. In the following description the term "nail" will be used frequently instead of fastening in describing the various mechanisms and the various operations performed by the machine, such use of the term nail being simply for convenience and not by way of limitation.

40 Referring to the drawings:

Figure 1 is a side view of the upper part of a loose nailing machine incorporating a preferred embodiment of the present invention;

45 Fig. 2 is a front view of the part of the machine shown in Fig. 1;

Fig. 3 is a vertical section showing in detail the means for connecting the two awl mechanisms with which the machine is provided;

50 Fig. 4 is a detail plan view of the raceways and separators;

Figs. 5 and 6 are two side views at right angles of the parts shown in Fig. 4;

55 Figs. 7 and 8 are, respectively, a plan and side view of the auxiliary separator; and

Fig. 9 is a diagrammatic representation of the relative disposition of the nails when two rows of nails are driven by the illustrated machine.

60 As is usual in machines of the type hereinbefore referred to, the illustrated machine, like the machine of said Letters Patent, is provided with a raceway adapted to receive previously formed headed nails from a hop-

per, a separator for separating the endmost nail from the line of nails in the raceway and movable to present the nail for the operation of a nail driver, and an awl having reciprocating movement to penetrate the shoe for forming successively nail receiving openings in the shoe and lateral movement to feed the shoe between successive nail inserting operations of the driver. The awl, separator, nail throat and nail driver are 70 carried by a swinging head which is operated after the awl has been moved downwardly to pierce the shoe to cause the awl to feed the work. The awl is then raised out of the work and the swinging head is 80 swung reversely to carry the nail throat and nail driver into positions over the nail receiving hole just made by the awl, after which the nail driver is operated to drive a nail into the said previously formed hole, 85 the shoe during the nail driving operation being clamped between a work support on which it is mounted and a work plate secured to the machine frame. For a complete disclosure and description of the construction and operation of the before-mentioned parts of the machine reference should be had to said prior Letters Patent, since conveniently, and as shown, these parts may be substantially like corresponding parts of 95 the machine of said Letters Patent.

Referring to the drawings, the illustrated machine has a supporting frame comprising a base, a standard or column 2 and a head 14. In the head 14, as hereinbefore stated, 100 are mounted the various parts of the fastening inserting, awl and separator mechanisms.

Mounted in a guideway in the swinging head 14 is a driver bar 4 (Fig. 2). For reciprocating the driver bar 4 the upper end of the driver bar is connected by a ball joint to a link 6, in turn connected to a lever 8 operated when permitted to force the driver bar downwardly by a spring 9, the driver bar 4 being lifted against the tension of the driving spring 9 by a driving cam indicated at 21 carried on the front end of the main driving shaft 23 and operated in the rotation of said shaft to engage a block 27 projecting from the driver bar 4. The driving shaft 23 is driven from a loose pulley 29 which may be clutched to the shaft at the will of the operator by suitable clutch mechanism. In accordance with the present invention, the driver bar 4 carries depending from its lower end both a driver 104 and an auxiliary driver 106 in front and at one side of the nail driver 104 (Fig. 4).

For penetrating a shoe to form fastening receiving openings in the shoe and moving the shoe to impart feeding movements thereto between successive fastening insertions, the head 14 carries, mounted for reciprocation therein, an awl bar 16 having depend-

ing therefrom an awl 18. For reciprocating the awl bar 16 to cause the awl 18 to penetrate the work and subsequently, after the work feeding movement, to be withdrawn from the work, the awl bar 16 is provided with teeth 31 (Fig. 2) arranged to engage the teeth of a toothed segment 33 carried at the outer end of a rock shaft 35, swinging movement being imparted to the head 14 to effect lateral shoe feeding movement of the awl 18 by a cam operated rock shaft and connections fully described in said prior Letters Patent.

Mounted in front and at one side of the awl 18 is an auxiliary awl 10 depending from an auxiliary awl bar 12 mounted for reciprocation in the swinging head 14 and for shoe feeding movement when the head 14 is swung.

To provide for effecting work penetrating reciprocating movement of the auxiliary awl 10 when desired, the machine is provided with means for connecting the auxiliary awl bar 12 to the awl bar 16 in such manner that when the awl bar 16 is moved downwardly to penetrate the work, the auxiliary awl bar 12 and auxiliary awl 10 will simultaneously and correspondingly be moved downwardly to effect work penetrating movement of the auxiliary awl 10. As shown, these means comprise a connecting pin 24 (Fig. 3) slidably mounted in a bearing 20 formed in a projection from the auxiliary awl bar 12, the said projection extending through a slot 22 formed in the front of the swinging head 14.

The pin 24 is adapted to be projected into a slot 26 in the awl bar 16 to connect the auxiliary awl bar 12 and the awl bar 16.

To permit moving the pin 24 into and out of the slot 26 to connect and disconnect the awl bar 16 and auxiliary awl bar 12 at will, the pin 24 is arranged to project beyond the end of its bearing 20 (looking toward the left, Fig. 3) and is connected to an operating lever 28 (Fig. 2). One end of the operating lever 28 is pivoted at 25 to the swinging head 14, while the other end of the lever 28 is operatively connected, by means to be described, to a knee lever not shown which, when shifted in one or the other direction, causes the pin 24 to be moved into or out of the slot 26, thus throwing the auxiliary awl mechanism into or out of operation.

For operatively connecting the pin 24 to the lever 28 for movement therewith, the lever 28 is provided with an enlarged portion 30 having therein a slot 32 into which slot one end of the connecting pin 24 projects (Fig. 3), a cross pin 34 passing through the enlarged portion 30 of the lever 28 and through said end of the connecting pin 24 and being secured to the connecting pin 24 by any suitable means. The slot 32 in the operating lever 28 and the slot 22 in the

swinging head 14 allow the auxiliary awl bar 12 to reciprocate, it being understood that the connecting pin 24, cross pin 34 and auxiliary awl bar 12 all reciprocate together.

For operating the lever 28 to control the operation of the auxiliary awl 10 and auxiliary awl bar 12 by shifting the pin 24 as above described, the end 36 (Fig. 1) of the lever 28 is pivoted to one end of a link 38, the other end of which is pivoted to one end of an arm of an elbow lever 40 fulcrumed on the machine frame. The end 36 of the lever 28 is provided with bearing faces which slide between lugs 42 (Fig. 1) projecting from the swinging head 14. The free end of the other arm of the elbow lever 40 is connected through suitable mechanism to a knee lever. When the knee lever is moved in one or the other direction the elbow lever 40, and through the connections from the elbow lever 40 to the lever 28, the lever 28 will also be moved in one or the other direction, whereby the connecting pin 24 will be shifted either into or out of the slot 26 so that the auxiliary awl bar 12 will be thereby either connected to or disconnected from the awl bar 16, and the auxiliary awl 10 will be consequently rendered either operative or inoperative, the auxiliary awl bar 12 being normally held raised by a spring 44 secured at one end to the auxiliary awl bar 12 and at the other end to the swinging head 14.

Preferably, and as shown, to prevent damage to the parts of the machine, the machine is provided with means for preventing throwing the auxiliary awl mechanism either into or out of operation during a predetermined part of the cycle of operations of the machine. To this end the machine has a locking member 46 (Fig. 1) mounted for reciprocation in a slideway formed in the upstanding arm of the elbow lever 40. The sliding locking member 46 is operated into locking position by connections from the awl mechanism operating shaft 35, a spring 48 (Fig. 1) being mounted below and partly within the locking member 46 to raise the locking member 46 to its normal inoperative position when permitted. The connections from the movable locking member 46 to the awl mechanism operating shaft 35, as shown and as fully set forth in United States Letters Patent No. 922,447, granted May 24, 1909, on an application of Bates and Gamble (see particularly Figs. 1 and 2 of said Letters Patent), comprise an arm 50 on the awl operating shaft and a ball-ended link 52, one end of which link projects into a recess 54 formed in the upstanding lug on arm 50 and bears against and is partly inclosed in one end of a plug 56 in said recess 54, the plug 56 having a shank 58 threaded into a projection from said lug on said arm and being held in position by means of a nut 60. The other end of the

link 52 is provided with a socket 62 adapted to receive a ball 64 forming the upper end of a screw 66 threaded into the locking member 46 and providing for adjustment of said locking member.

The locking member 46 carries a block 68 adjustably secured to said locking member by a screw 70, the said block having two notches or recesses 72 formed therein, one 10 on each side. Pivoted to the frame of the machine is a stationary locking member 74 adjustable about its pivot by means of screws 76 which engage the stationary locking member 74 at either side of its pivot and hold it firmly in adjusted position. The locking member 74 is also provided with an arm 78 having a bearing for one end of a ball-ended link 81, the other end of which link is seated within one end of a plug 80 20 secured in a projection from the machine frame, the plug 80 assisting to hold the locking member 74 in adjusted position. To enable the stationary locking member 74 to co-operate with the movable locking member 46 to secure the elbow lever 40 against movement when desired, the stationary locking member 74 carries on each side of the axis of its pivot a block 82, each of the blocks 82 having a tooth or knife edge, one or the other of which is received in the corresponding recess 72 in the block 68 upon downward operative movement of the movable locking member 46.

The construction and arrangement are such that the movable locking member 46 is automatically moved downwardly to cause one or the other of the knife edges projecting from the block 82 on the stationary locking member 74 to enter the corresponding recess 72 in the block 68 on the said locking member 46 upon downward shoe penetrating awl movement. By this construction and arrangement the elbow lever 40 is locked against movement either to connect or disconnect the awl mechanisms while a shoe is being fed. It will be understood that the position of the knee lever 40 when operative locking movement is imparted to the movable locking member 46 will determine which knife edge is caused to enter the corresponding recess, one knife edge and recess co-operating to lock the elbow lever 40 when the elbow lever 40 is in the position in which the awl mechanisms are connected and the other knife edge and recess co-operating when the elbow lever 40 is in position for effecting disconnection of the awl mechanisms. Conveniently, stops 47 carried by the machine frame are arranged to limit the movement of the elbow lever 40 in one or the other direction.

In addition to the driver mechanisms and awl mechanisms before described, in order to adapt the machine for inserting simultaneously a plurality of rows of fastenings

when desired, as previously mentioned the machine is provided with a plurality of raceway mechanisms for supplying previously formed headed nails and a plurality of nail separator mechanisms for governing the supply of nails from the raceways.

For supplying nails to the separators, the machine is provided with a raceway 84 and an auxiliary raceway 88 (Fig. 4) constructed and arranged to hold previously formed headed nails. The separator mechanisms comprise a separator 86 (Fig. 4) and operating means therefor, and an auxiliary separator 90 and operating means for the auxiliary separator. The separator 86 is carried at the lower end of a lever 91 (Fig. 2) fulcrumed at 93 on the swinging head 14 and provided at its upper end with a roller 95 which bears against a cam face forming part of the cam disk indicated at 21. A suitable strong spring 97 attached to the swinging head 14 operates to maintain the roller 95 in engagement with its operating cam. As shown, the separator 86 is of a well-known construction and need not be described in detail herein, the described construction and arrangement providing for reciprocating the separator 86 to cause its blade end to be inserted between the end-most nail in the line of nails in the raceway 84 and the adjacent nail and to move said end-most nail to present it for the operation of its driver. The auxiliary separator 90 is carried at the lower end of a depending lever 92 (Fig. 1) pivoted at 94 to the swinging head 14.

In the illustrated machine, the auxiliary separator and the auxiliary awl mechanism are constructed and arranged to be controlled simultaneously, provision being made for causing initiation and suspension of the operation of the auxiliary separator to be controlled by the initiation and suspension of the operation of the auxiliary awl mechanism. To this end, the auxiliary separator lever 92 carries at its lower end a roller 96 adapted to engage a cam face 98 formed on the auxiliary awl bar 12, the construction and arrangement being such that when the auxiliary awl 10 is moved downwardly the cam face 98 will engage and swing the auxiliary separator lever 92 to move the auxiliary separator 90 into its retracted position in readiness to perform a nail separating operation. On the upward movement of the auxiliary awl 10 after it has pierced and fed the work, the auxiliary separator lever 92 will be swung forwardly again by means of a spring 100 and will be caused to separate and feed a nail from its raceway. It will be apparent that when the auxiliary awl bar 12 is disconnected from the awl bar 16 and thereby rendered inoperative, the auxiliary separator lever 92 will also be rendered inoperative. As shown, the ex-

treme inward position of the auxiliary separator lever (Fig. 1) may be varied by means of an adjusting screw 102 adapted to engage one face of the auxiliary awl bar 12.

5 From the foregoing description, it will be apparent that upon movement of the knee lever to operate the elbow lever 40 one way or the other, the auxiliary awl and separator mechanisms will thereby be rendered 70 either operative or inoperative, and either one or two rows of nails will be driven at the will of the operator; movement of the elbow lever 40 to disconnect the auxiliary awl bar 12 from the awl bar 16 operating 75 simultaneously to cause the operation of the auxiliary separator lever 92 to be suspended, whereupon the machine will insert one row of fastenings only, the auxiliary driver 160 reciprocating idly.

20 The illustrated machine is provided with the usual work abutment indicated at 108 (Fig. 1) and a roller 109 is introduced between the swinging head 14 and the abutment 108 to bear the upward thrust of the 25 shoe and at the same time to allow the head 14 to swing to cause the shoe to be fed. In the use of the machine the work is supported upon a horn 134 between which and the abutment 108 the shoe is clamped whenever a fastening is to be inserted, as is usual 30 in machines of this type, the abutment 108 being provided with a hardened work plate 132 which operates to press down any nails which may not have been driven flush 35 with the shoe bottom. The machine is also provided with an edge guide 110 secured to a slide in the frame of the machine and provided with an upwardly extending portion 114 having a cutaway part 116 into which 40 projects one arm 118 of a lever fulcrumed on the machine at 119, the other arm 120 of which lever forms a handle for the purpose of moving the edge gage 110 into different adjusted positions. In the illustrated construction the edge gage 110 is provided with a stop pin 126 extended between two downwardly projecting lugs 122 formed on an adjustable plate 127 secured to the frame of the machine by means of screws 128 passing 45 through slots 130 formed in said plate 127. As shown, the lugs 122 are spaced apart a distance equal to the distance between the two rows of nails α and β (Fig. 9) formed when the machine is used for 50 double row nailing for the purpose of allowing the operator, if desired, to move the edge gage 110 quickly and conveniently to cause the nail driver 104 to insert fastenings in the line of operation of the auxiliary 55 nail driver 106 when only one row of fastenings is to be inserted in a shoe.

In the use of the illustrated machine, assuming that it is desired to drive simultaneously a double row of nails, the knee lever 60 is first moved to connect the auxiliary awl

bar 12 to the awl bar 16 through the link 38 and lever 28, the connecting pin 24 thereby rendering the auxiliary awl 10 and the auxiliary separator 90 operative. Upon downward movement of the awl bar 16 effected through its rack and segment connection with the cam operated rock shaft 35, the awls 10 and 18 will be forced downwardly simultaneously to cause them to penetrate the shoe and form therein fastening 70 receiving openings, the auxiliary awl 10 making a hole at one side of that made by the awl 18 and at a point spaced inwardly from the edge of the shoe farther than the hole made by the awl 18. As the auxiliary 75 awl 10 descends, the cam face 98 formed on its awl bar 12 will swing the auxiliary separator lever 92 and move the auxiliary separator 90 into a position in readiness to separate the endmost nail from the line of nails 80 in the auxiliary raceway 88. The head 14 then swings in a direction to cause the awls to feed the work, the nail drivers and separators being swung with the awls in a direction to feed the shoe. The shoe having 85 been fed, the awl bar 16 is then raised, thereby withdrawing the awls 10 and 16 from the shoe, the upward movement of the auxiliary awl bar 12 permitting the auxiliary separator lever 92 to be swung about its 90 pivot 94 by the spring 100, thereby causing the auxiliary separator to perform a nail separating operation. Simultaneously with the nail separating movement of the auxiliary separator 90 the separator 86 delivers 100 a nail from the raceway 84.

The head 14 is then swung reversely to bring the drivers 104, 106 into positions above the fastening receiving openings made by the awls. The work is then 105 clamped in the usual manner between the work plate 132 and the horn 134. Thereafter, the nail drivers are forced downwardly by the spring 9 to drive simultaneously 110 a pair of nails into the holes formed by the awls 10 and 12. As this cycle of operations of the machine is repeated, two rows, each comprising successively inserted nails, are driven into the shoe simultaneously, the before described relative positions of the awls and drivers being such that, as indicated in Fig. 9, the row of nails α inserted by the auxiliary driver 106 is located farther from the edge of the shoe than the row of nails β inserted by the 115 driver 104, the two rows being substantially parallel. By reason of the fact that the auxiliary awl 10 and auxiliary driver 106 are located at one side of the awl 18 and driver 104 respectively, the nails of the two 120 rows α and β are driven staggered, as shown in Fig. 9. Obviously, however, if desired the relative arrangement of the rows α and β and the relative positions of the nails in those rows may be varied readily by ad- 125 130

justing the relative positions of the awls and drivers.

While the shoe is being fed by the awls 10 and 18, the sliding locking member 46 will 5 automatically be forced downwardly through its described connection with the awl mechanism operating shaft 35 to cause one of the notches 72 to overlap one of the teeth 82, thereby locking the knee lever and elbow 10 lever 40 against movement, and thereby preventing movement of the pin 24. Upon subsequent upward movement of the awls after the completion of the shoe feeding movement, the movable locking member 46 will 15 be raised to its normal position by its operating spring 48, unlocking the elbow lever 40 and knee lever and permitting manipulation thereof to connect or disconnect the awl mechanisms, and thereby to render opera- 20 tive or inoperative the auxiliary separator mechanism.

Having fully explained the present invention and described in what manner the same may be embodied, what I claim as new and 25 desire to secure by Letters Patent of the United States is:—

1. In a machine of the class described, in combination, awl mechanism, raceway mechanism for supplying previously formed 30 fastenings, separator mechanism for governing the supply of fastenings from the raceway mechanism, auxiliary awl mechanism, auxiliary separator mechanism, and means for controlling the operation of said auxiliary awl and separator mechanisms simultaneously.

2. In a machine of the class described, the combination with awl mechanism, raceway mechanism for supplying previously 40 formed fastenings, and separator mechanism for governing the supply of fastenings from the raceway mechanism, of auxiliary awl mechanism, auxiliary separator mechanism, and a controller operating to throw said auxiliary awl and separator mechanisms simultaneously into or out of operation.

3. In a machine of the class described, in combination, awl mechanism, a plurality of fastening raceways, fastening separators for governing the supply of fastenings from the raceways, auxiliary awl mechanism, and means for simultaneously controlling the operation of one of said separators and said auxiliary awl mechanism.

4. A machine of the class described having, in combination, awl mechanism for forming fastening receiving openings in a shoe successively, raceway mechanism for supplying previously formed fastenings, 55 separator mechanism for governing the supply of fastenings from the raceway mechanism, a driver for inserting a row of fastenings successively in the fastening receiving openings formed by said awl mechanism,

auxiliary awl mechanism, an auxiliary separator, an auxiliary driver, and means for simultaneously throwing said auxiliary awl and separator mechanisms into or out of operation to cause one or more rows of fastenings to be inserted in the shoe. 65

5. A machine of the class described having, in combination, mechanism for inserting a plurality of fastenings successively in a shoe to form a row, a raceway mechanism for supplying previously formed fastenings 70 to the fastening inserting mechanism, a separator mechanism for governing the supply of fastenings from the raceway mechanism, and a co-acting auxiliary fastening inserting mechanism, said fastening inserting 75 mechanisms constructed and arranged to insert in the shoe substantially simultaneously a plurality of rows each comprising successively inserted fastenings. 80

6. A machine of the class described having, in combination, a raceway mechanism for holding and supplying previously formed headed nails, a separator mechanism for governing the supply of nails from the raceway mechanism, nail driving mechanism 90 comprising a driver and means for reciprocating the driver to insert a plurality of said nails successively in a shoe to form a row, an auxiliary nail separator mechanism, and auxiliary nail driving mechanism, said nail 95 driving mechanisms coacting to insert simultaneously in the shoe a plurality of rows, each comprising successively inserted nails. 100

7. A machine of the class described having, in combination, an awl mechanism for forming fastening receiving openings successively in a shoe, a raceway mechanism for supplying previously formed fastenings, a separator mechanism for governing the supply of fastenings from the raceway 105 mechanism, an auxiliary awl mechanism, and coacting fastening inserting mechanisms constructed and arranged to insert simultaneously a plurality of rows of fastenings in the fastening receiving openings formed 110 by said awl mechanisms.

8. A machine of the class described having, in combination, an awl mechanism for forming fastening receiving openings in a shoe, raceways for supplying previously 115 formed fastenings, separators for governing the supply of fastenings from the raceways, an auxiliary awl mechanism, and fastening inserting mechanism comprising co-acting drivers each constructed and arranged to insert fastenings successively in the fastening openings formed by the corresponding awl mechanism, said drivers being arranged to form substantially simultaneously a plurality of rows of said fastenings. 120

9. A machine of the class described having, in combination, awl mechanism, raceway mechanism for supplying previously

formed fastenings, separator mechanism for governing the supply of fastenings from the raceway mechanism, an auxiliary awl mechanism, an auxiliary separator mechanism, 5 mechanism for inserting fastenings successively to form a row, auxiliary fastening inserting mechanism, and means for throwing said auxiliary awl and separator mechanisms into and out of operation to cause 10 one or more rows of fastenings to be inserted as desired.

10. A machine of the class described having, in combination, an awl for forming in a shoe fastening receiving openings successively in a row, raceway mechanism for supplying previously formed fastenings, separator mechanism for governing the supply of said fastenings from the raceway mechanism, an auxiliary awl, said awls being laterally displaced relatively to each other to cause one of said rows of fastening receiving openings to be inserted farther from the edge of the shoe than the other row, and fastening inserting mechanism comprising 25 drivers constructed and arranged to insert simultaneously rows of fastenings in said fastening receiving openings formed by said awls.

11. A machine of the class described having, in combination, a reciprocating awl carrier, an awl depending from said carrier for forming in a shoe fastening receiving openings successively in a row, raceway mechanism for supplying previously formed fastenings, separator mechanism for governing the supply of said fastenings from the raceway mechanism, an auxiliary awl carrier, an auxiliary awl depending from the auxiliary awl carrier, said auxiliary awl 30 carrier being laterally displaced relatively to said first-named awl carrier to cause one of said rows of fastening receiving openings to be spaced inwardly from the edge of the shoe beyond the other row and disposed substantially parallel to said other row, and fastening inserting mechanism comprising drivers disposed correspondingly to said awls and constructed and arranged to insert simultaneously rows of fastenings in the fastening receiving openings formed by said awls.

12. A machine of the class described having, in combination, an awl for forming in a shoe fastening receiving openings successively in a row, raceway mechanism for supplying previously formed fastenings, separator mechanism for governing the supply of said fastenings from the raceway mechanism, an auxiliary awl constructed and arranged relatively to said first-named awl to form a row of fastening receiving openings spaced from and staggered with relation to the openings in said first-named row, and fastening inserting mechanism

comprising drivers constructed and arranged to insert simultaneously rows of fastenings in the fastening receiving openings formed by said awls. 65

13. In a machine of the class described, awl mechanism, raceway mechanism for supplying fastenings, separator mechanism for governing the supply of fastenings from the raceway mechanism, auxiliary awl mechanism, and auxiliary separator mechanism controlled by the auxiliary awl mechanism. 70

14. In a machine of the class described, awl mechanism, raceway mechanism for supplying previously formed fastenings, separator mechanism for governing the supply of fastenings from the raceway mechanism, auxiliary awl mechanism, and auxiliary separator mechanism constructed and arranged to be rendered operative upon movement of said auxiliary awl mechanism, whereby the operation of said auxiliary separator 80 mechanism is controlled by said auxiliary awl mechanism.

15. In a machine of the class described, awl mechanism, raceway mechanism for supplying fastenings, separator mechanism for governing the supply of fastenings from the raceway mechanism, auxiliary awl mechanism, and auxiliary separator mechanism constructed and arranged to be moved by said auxiliary awl mechanism into position for nail separating movement. 90

16. In a machine of the class described, awl mechanism, raceway mechanism for supplying fastenings, separator mechanism for governing the supply of fastenings from the raceway mechanism, auxiliary awl mechanism, an auxiliary separator mechanism normally projecting into the path of movement of the auxiliary awl mechanism to cause the auxiliary separator to be moved into retracted position upon movement of the auxiliary awl mechanism in one direction, and means for imparting nail separating movement to said auxiliary nail separator when permitted by said auxiliary awl mechanism. 100

17. In a machine of the class described, awl mechanism comprising an awl carrier, an awl carried thereby, raceway mechanism for supplying fastenings, separator mechanism for governing the supply of fastenings 115 from the raceway mechanism, an auxiliary awl, a reciprocating carrier for said auxiliary awl, a cam face on said carrier, an auxiliary separator, a swinging lever carrier for said auxiliary separator normally projecting into the path of movement of said cam face and constructed and arranged to be swung to bring the auxiliary separator into retracted position through engagement with said cam face upon movement of said 120 auxiliary awl carrier in one direction, means for imparting nail separating movement to the auxiliary nail separator carrier when

permitted by said auxiliary awl carrier, and means for operatively connecting said auxiliary awl carrier to said first-named awl mechanism for reciprocation therewith.

5 18. In a machine of the class described, in combination, fastening inserting mechanism, raceway mechanism for supplying previously formed fastenings to the fastening inserting mechanism, separator mechanism for governing the discharge of fastenings from the raceway mechanism, an awl, an auxiliary awl normally in inoperative relation to said first named awl, and means for operatively connecting said auxiliary awl with said first named awl for operation therewith.

10 19. In a machine of the class described, a reciprocating awl bar, an awl carried by said awl bar, an auxiliary awl bar normally independent of said first-named awl bar, an auxiliary awl carried by said auxiliary awl bar, and means for connecting said auxiliary awl bar with said first-named awl bar for reciprocation therewith.

15 20. In a machine of the class described, a reciprocating awl bar, an awl carried by said awl bar, an auxiliary awl bar, an auxiliary awl carried by said auxiliary awl bar, and manually controlled means operable during the operation of the machine for connecting said auxiliary awl bar with said first-named awl bar for reciprocation therewith.

25 21. In a machine of the class described, a reciprocating awl bar, an awl carried by said bar, an auxiliary awl bar, an auxiliary awl carried by said auxiliary awl bar, an element for operatively connecting said auxiliary awl bar and said first-named awl bar, and a controller operatively connected to said element for initiating and suspending the operation of said auxiliary awl bar upon movement of the controller.

35 22. In a machine of the class described, a reciprocating awl bar, an awl carried by said awl bar, an auxiliary awl bar, an auxiliary awl carried by said auxiliary awl bar, a shiftable pin for connecting said auxiliary awl bar to said first-named awl bar for reciprocation therewith, a manually operable controller, and lever connections from said controller to said pin.

45 23. In a machine of the class described, awl mechanism, raceway mechanism for supplying fastenings, separator mechanism for governing the supply of fastenings from the raceway mechanism, auxiliary awl mechanism, auxiliary separator mechanism, means for throwing said auxiliary awl and separator mechanisms into and out of operation, and means operable to prevent said auxiliary mechanisms being thrown into or out of operation during a predetermined part of the cycle of operations of the machine.

55 24. In a machine of the class described,

awl mechanism, raceway mechanism for supplying fastenings, separator mechanism for governing the supply of fastenings from the raceway mechanism, auxiliary awl mechanism, auxiliary separator mechanism, a controller for said auxiliary awl and separator mechanisms, and means for automatically locking said controller against movement during a predetermined part of the cycle of operations of the machine.

75 25. A machine of the class described having, in combination, awl mechanism for feeding a shoe between successive fastening insertions, fastening inserting mechanism, raceway mechanism for supplying fastenings to the inserting mechanism, fastening separator mechanism for governing the supply of fastenings from the raceway mechanism, an auxiliary awl mechanism, an auxiliary separator mechanism, means for controlling the operation of said auxiliary awl and separator mechanisms, and means operating automatically to lock said controlling means against operative movement while the shoe is being fed.

80 26. In a machine of the class described, an awl mechanism constructed and arranged to form fastening receiving openings in a shoe and feed the shoe between successive fastening insertions, a raceway mechanism for supplying fastenings, a separator mechanism for governing the supply of fastenings from the raceway mechanism, an auxiliary awl mechanism, an auxiliary separator mechanism, a controller for throwing said auxiliary awl and separator mechanisms into and out of operation, a member movable to lock said controller against movement, and means for operating said locking member upon shoe penetrating movement of said awl mechanism to prevent movement of said controller while the shoe is being fed.

90 27. In a machine of the class described, an awl, means for reciprocating said awl to form fastening receiving openings in a shoe, means for imparting lateral movement to the awl while the awl is in the shoe to feed the shoe between successive fastening insertions, raceway mechanism for supplying fastenings, separator mechanism for governing the supply of fastenings from the raceway mechanism, auxiliary awl mechanism, auxiliary separator mechanism, a controller for said auxiliary awl and separator mechanisms, and a locking member operated by said awl reciprocating means upon shoe penetrating movement of said awl to lock said controller against movement while the work is being fed.

95 28. In a machine of the class described, awl mechanism for forming fastening receiving insertions in a shoe and feeding the shoe between successive fastening insertions, raceway mechanism for supplying fasten-

- ings, separator mechanism for governing the supply of fastenings from the raceway mechanism, auxiliary awl and separator mechanisms, a controller for said auxiliary mechanisms, a stationary locking member, and a locking member carried by said controller and movable into engagement with the stationary locking member to prevent movement of the controller.
29. In a machine of the class described, awl mechanism for forming fastening receiving insertions in a shoe and feeding the shoe between successive fastening insertions, raceway mechanism for supplying fastenings, separator mechanism for governing the supply of fastenings from the raceway mechanism, auxiliary awl mechanism, auxiliary separator mechanism, a lever for controlling the operation of said auxiliary awl and separator mechanisms, a locking member mounted for sliding movement in said lever, a co-operating stationary locking member, one of said locking members having projections therefrom and the other having corresponding recesses formed therein, and means for moving said first-named locking member to cause one or the other of said projections to enter the corresponding recess, according to the position of said lever.
30. In a machine of the class described, awl mechanism, raceway mechanism for supplying fastenings, separator mechanism for governing the supply of fastenings from the raceway mechanism, auxiliary awl mechanism, auxiliary separator mechanism, an elbow lever operatively connected to the auxiliary awl and separator mechanisms to control the operation of said mechanisms, and means for locking said elbow lever against movement during a predetermined part of the cycle of operations of the machine, said means comprising a slide carried by the elbow lever, a stationary member having parts adapted for interlocking engagement with said slide, an operating member for said slide, and a ball and socket connection between said operating member and said slide.
31. A machine of the class described having, in combination, mechanism for inserting a plurality of previously formed fastenings successively in a shoe to form a row, raceway mechanism, separator mechanism for governing the supply of fastenings from the raceway mechanism to the inserting mechanism, co-acting auxiliary fastening inserting mechanism operable to insert in the shoe a second row of fastenings simultaneously with the insertion of the first-named row, an edge gage, a stationary plate provided with depending lugs spaced apart the distance between said rows of fastenings, and a stop pin projecting from said edge gage between said lugs to determine the distance from the edge of the shoe of the row of fastenings formed by said first-named inserting mechanism, said edge gage being shiftable at will to cause said first-named inserting mechanism to insert fastenings in the line of operation of said auxiliary fastening mechanism if desired when only one row of fastenings is to be inserted in a shoe.
32. In a machine of the class described, in combination, awl mechanism, raceway mechanism for supplying previously formed fastenings, separator mechanism for governing the supply of fastenings from the raceway mechanism, auxiliary awl mechanism, auxiliary separator mechanism, and means for controlling the operation of said auxiliary awl and separator mechanisms.
33. A machine of the class described having, in combination, a raceway mechanism for holding and supplying fastenings, a separator mechanism for governing the supply of fastenings from the raceway mechanism, mechanism constructed and arranged to insert fastenings into the work in planes spaced laterally relatively to the direction of movement of the work, awl mechanism constructed and arranged to form openings in the work to receive the driven fastenings, and means for operating the awl mechanism to feed the work, said fastening inserting mechanism and awl mechanism co-acting to insert simultaneously in the shoe a plurality of rows, each comprising successively inserted fastenings.

In testimony whereof I have signed my name to this specification.

THOMAS BRIGGS.
